UNITED STATES PATENT OFFICE.

WILLIAM MARTIN, OF NEW YORK, N. Y.

MACHINE FOR EDGING SHEET-METAL ROOFING-PLATES.

SPECIFICATION forming part of Letters Patent No. 655,903, dated August 14, 1900.

Application filed October 31, 1899. Serial No. 735,353. (No model.)

To all whom it may concern:

Be it known that I, WILLIAM MARTIN, a citizen of the United States, and a resident of the borough of Manhattan, in the city and 5 State of New York, have invented a new and useful Machine for Edging Sheet-Metal Roofing-Plates, of which the following is a specification.

My invention relates to a machine for edging sheet-metal roofing-plates, with the object in view of providing means for automatically transferring the plates one after another from a stack to the position where their 15 edges will be acted upon and bent in the desired directions and then allowing them to drop onto a receiver.

The so-called "edging" of roofing-plates consists in bending a side and one end of the plate over toward the body of the plate in one 20 direction and the remaining side and end of the plate over in the opposite direction.

My present invention contemplates mechanically feeding the plates to and discharging them from the bending-tools and simultaneously bending the four edges by mechanical means alone, thereby materially reducing 25 the cost of labor.

In the accompanying drawings, Figure 1 is a view of the machine in side elevation. Fig. 30 2 is a top plan view. Fig. 3 is an end view. Fig. 4 is an enlarged partial vertical longitudinal section along the line 4-4 of Fig. 2, showing the bending-tools in the position which they occupy before the bending operation begins. Fig. 5 is a similar view showing the position 35 of the bending-tools when the operation of bending is completed, and Fig. 6 represents in perspective one of the edged sheets.

The bed-frame of the machine is denoted 40 by A and may be of any well-known or approved form suitable for supporting the several operating parts. Upon the bed-frame A shaft-supporting brackets a' are fixed, in which the main drive-shaft B is journaled and 45 provided with a suitable driving-pulley b, which may be connected with a source of power. (Not shown.) The drive-shaft B imparts motion to the several parts of the feeding, bending, and discharging mechanisms 50 by means of cams of various sizes and shapes and a crank, to which particular attention will be called.

The plates are transferred one after another from a stack to the bending mechanism by means of a pneumatic lifter. This pneumatic lifter consists of an arm C, hinged to a carriage c at c' to swing toward and away from the top of the stack of plates P. Its free end is provided with a mouth surrounded by lips c² of pliant material—such, for example, 55 as rubber or leather—and its mouth is connected with a suction-pump D by means of a flexible pipe d. With each revolution of the shaft B a lifter p under the stack of plates P is raised by a cam b', fixed on the shaft 60 and adapted to engage a vertically-movable pin p' on one arm of a rocking lever p², fulcrumed in a bracket a², depending from the bed-frame A. At the same time the stack of plates is lifted by the lifter p the piston in 65 the suction-pump D is operated by an arm d', pivoted to an uprising bracket a³ on the bed-frame and operated by a cam b² on the drive-shaft. Thus when the uppermost plate of the stack P is brought into close contact with the 70 lips c² at the mouth of the lifter suction will be applied through the pipe d and the plate will be held to the lifter until the suction is released. The plate is held to an arm C, while 75 the said arm is lifted by a swinging frame E 80 hinged to uprights a⁴ a⁵ of the bed-frame, and subject in turn to be swung upwardly by means of a cam b³ on the drive-shaft B and while so lifted is carried bodily along the machine from a position over the stack 85 to a position above where it is to be bent by means of the carriage c, which is slid along a way a⁶ on the bed-frame by means of a pitman c³, connected with a crank b⁴ on the drive-shaft. After reaching a point over the 90 position where it is to be bent the cam b³ gradually lowers the swinging frame E, thereby 95 lowering the arm C until the plate carried by the arm C nears the position where it is to be bent, and at this moment the cam releases the suction on the pump D, thereby permitting the plate to drop into position to be bent, and the cam b³ and crank b⁴ proceed to return the arm C to its normal position, while the further rotary movement of the 100 shaft B operates the bending-tools.

Before the plate reaches the position where it is to be bent the combined anvil-support and discharge has been swung into position

650,303

beneath the plate ready to receive it. This combined anvil-support and discharge device is fixed to a comparatively-thin angle-plate F, two of its edges f, f' being adapted 5 to form guides down over which two adjacent edges of the plate are to be bent. The angle-plate F is conveniently made a prolongation of an arm f², fixed to a bearing f⁴, loosely mounted on a spindle f⁵ and permitted a limited vertical movement on said spindle, 10 the said bearing being provided with a short arm f⁶ in position to engage a cam b⁵ on the shaft B, by which the angle-plate F is swung into position to support the plate while being bent and out of position, as shown in dotted lines, Fig. 2, to discharge the plate after the edges of the plate have been bent. In its movement into position to receive the plate to be bent the angle-plate F is gradually 15 lifted by the engagement of the arm f² (see Fig. 3) with a stationary cam f⁷ in order to permit it to pass beneath the bending mechanism at the edge of the plate, and a portion of the said angle-plate F, adjacent to the 20 arm f², is provided with a band, as shown at f⁸, Fig. 1, to permit it to rest in its elevated adjustment when it reaches its position without interfering with the bending mechanism at the edge. The angle-plate F is forced into 25 its position to support the plate while being bent by means of the cam b⁵ on the drive-shaft and is returned to its position to discharge the plate by means of a spring f⁹, connected at one end to the arm f² and at 30 its opposite end to a suitable support—in the present instance to the standard a⁵. A similar angle-plate F', with edges adapted to form guides up over which the remaining two edges of the plate to be bent are forced 35 by the bending mechanism, is secured to a bearing f¹⁰, mounted on a spindle f¹¹, fixed in the bed-frame and permitted a limited vertical movement on said spindle. The bearing f¹⁰ is pressed normally toward its ele- 40 vated position on the spindle f¹¹ by means of a coil-spring f¹² for the purpose of carrying the angle-plate F' over the bending mechanism at the edge of the plate to be operated upon, and in order that the angle-plate F' 45 may rest in its lowered position on the plate after reaching its position over the plate it has its neck curved upwardly, as shown at f¹³. The said angle-plate is forced down into its position on the plate by means of a fixed 50 cam f¹⁴ in position to engage the shank of the angle-plate as it nears its position over the plate to be bent. This angle-plate F' is operated by means of a rod G, connected with a short arm f¹⁵ on the bearing f¹⁰ and adapted 55 to be engaged by a cam b⁶ on the drive-shaft B. The cam forces the rod G in the direction to throw the angle-plate F' into position over the plate to be bent, and the said angle-plate F' is thrown away from this position to 60 receive a new plate by means of a spring g, inserted between the bracket a⁷ and a collar g', fixed on the rod G.

There are two bending-tools shaped and operated to bend the edges of the plate downwardly and inwardly over the guide-plate F, 70 which serves as an anvil during the bending operation, and two tools constructed and operated to bend adjacent edges of the plate up and over the edges of the angle-plate F', which also serves as an anvil for this purpose. These several tools are shown in plan in Fig. 2, while Figs. 4 and 5 represent one of each type of the tools in the position which they occupy when the plate is first laid upon them and the position which they assume 80 when the bending is completed. The tools for bending the edges downwardly and inwardly are denoted by H and H', the former being shown in section in Figs. 4 and 5 and the latter in face elevation in said figures, 85 while the two are shown in top plan in Fig. 2. It is to be understood, however, that the tool H' has a section substantially corresponding to the section of the tool H. When in its normal position, the tool H rests with a 90 projecting lip h in position to receive thereon the edge—in the present instance at the end of the plate to be bent—and a curved bending-finger h' extends upwardly from the lip or shoulder h. The length of the bending-tool 95 H corresponds to the length of the edge of the plate with which it engages and it is mounted to rock on a spindle h², supported in tops of flexible standards h³, fixed to the bed-frame A. A tailpiece h⁴ extends from the tool H and is 100 connected by a link h⁵ with a rocking arm h⁶ in position to be lifted by an operating-bar h⁷, fulcrumed on a bracket a⁸ and operated by a cam b⁷ on the drive-shaft B. A standard a⁹ is provided at its top with a curved 105 face h⁸ in position to engage the tailpiece h⁴ when the link h⁵ is lifted to bring the tool in engagement with the edge of the plate and serves to push the tool inwardly into the position shown in Fig. 5 to complete the bend 110 of the edge of the plate, the flexible standards h³ yielding to permit the tool to be bodily moved toward the plate. The same operating-bar h⁷ which lifts the arm h⁶ to operate the tool H is connected by a link h⁹ with the 115 tail of the tool H', which is mounted similarly to the tool H on flexible standards h¹⁰ h¹¹ and which is forced to operate on the edge of the plate in the same manner that the tool H operates on it—viz., to bend its edge downwardly 120 and inwardly over the edge f of the angle-plate F, which serves as an anvil for this purpose. The tool H' is forced bodily inwardly by the engagement of its tailpiece with the curved face of a standard a¹⁰ in a manner quite similar to that in which the tool H is forced in by engagement with the surface h⁸ on the standard a⁹. The tools for bending the other edges of the plate up and over the edges of the angle-plate or anvil F' are denoted by I and I', the former being shown in section in Figs. 4 and 5 and both being shown 125 in top plan in Fig. 2. These tools are quite similar in their general structure, and con- 130

sist of a hub portion from which projects a curved finger i , on which the edge of the plate rests when the tool is in its normal position before the bending operation begins. Like the tool H, I is mounted in a flexible standard or standards i' , fixed to the bed-frame, and its tailpiece i^2 is connected by a link i^3 with a rocking arm i^4 in position to be depressed by a lever i^5 , fulcrumed in a bracket a^{11} , fixed on the bed-frame and operated by a cam b^8 on the drive-shaft B. The same lever i^5 is connected with the tailpiece of the tool I' by means of a link i^6 . The tool I' is mounted in the ends of spring-actuated plates K K', (see Fig. 2,) having a limited horizontal sliding motion with respect to their supporting-plate a^{12} to permit the bending-tool to be forced bodily inward by the face of the standard a^9 in a manner quite similar to that in which the tool I is forced inwardly by the curved face of the standard i^8 . (See Figs. 4 and 5.)

By locating the yielding supports K K' in a horizontal plane above the path of the angle-plate or anvil F the latter is permitted a free swinging movement into and out of its position beneath the plate to be edged.

Just before the plate is deposited in position to be edged the angle-plate or anvil F is rocked into position to receive it, and after it has been deposited and while the lifting and feeding arm C is being returned to its position to pick up a succeeding plate the angle-plate and anvil F' is rocked into position above the plate. As soon as this is accomplished the bending-tools are simultaneously operated to bend two adjacent edges of the plates downwardly and inwardly and the remaining two edges upwardly and inwardly. This having been accomplished and while a succeeding plate is being picked up by the lifter, the angle-plates or anvils F F' are swung outwardly, permitting the plate, with its bent edges, to drop onto any suitable receiver on or below the bed A, and the tools are then returned to the position to receive another plate.

It is obvious that changes might be resorted to in the form and arrangement of the several parts without departing from the spirit and scope of my invention. Hence I do not wish to limit myself strictly to the structure herein set forth; but

What I claim is—

1. The combination with the bending-tools and means for operating them, of a sheet-lifting arm, means for imparting a rocking movement to the arm and means for moving the arm and sheet carried thereby bodily in a direction lateral to the rocking movement of the arm from the supply to the position where the plate is to be operated upon, substantially as set forth.

2. The combination with means for simul-

taneously bending the edges of a sheet and means for operating the bending means, of a sheet-lifting arm, a suction apparatus arranged to hold the sheet temporarily to the arm and means for moving the sheet and arm bodily from the supply to the point where the sheet is to be edged, substantially as set forth. 70

3. The combination with a drive-shaft, of bending-tools arranged to act simultaneously on the four sides of a sheet, sheet-conveying mechanism and a suction apparatus, and means for placing the tools, conveyer and suction mechanism under the control of the drive-shaft, substantially as set forth. 75

4. The combination with a set of bending-tools arranged to operate upon different edges of a sheet of metal and means for operating them, of a movable guide or anvil common to two adjacent sets of tools arranged to swing into and out of position to coöperate with the said tools, substantially as set forth. 80

5. The combination with tools arranged to bend different edges of a sheet of metal over toward opposite sides of the sheet, of anvils or guides arranged to swing into and out of position to coöperate with the said tools, substantially as set forth. 85

6. The combination with a yielding support, of a bending-tool mounted in rocking adjustment in said yielding support, means for automatically feeding a sheet of metal to the bending-tool, means for holding a sheet of metal in position to have its edge bent by said tool and means for simultaneously rocking the tool and forcing it bodily toward the edge of the sheet of metal, substantially as set forth. 95

7. The combination with sets of tools arranged to act upon different edges of a sheet of metal, of means for simultaneously operating one set of tools in one direction to bend an edge upward and over toward one face of the sheet and the other set of tools in the opposite direction, to turn an edge of the sheet downward and under toward the opposite face of the sheet, substantially as set forth. 105

8. The combination with tools arranged to simultaneously bend two adjacent edges of a sheet of metal over toward the one face of the sheet and tools arranged to bend, at the same time, another two adjacent edges of the sheet toward the opposite face of the sheet, of movable guides or anvils arranged to swing into and out of position to coöperate with the several bending-tools, substantially as set forth. 115

In testimony that I claim the foregoing as my invention I have signed my name, in presence of two witnesses, this 27th day of October, 1899.

WILLIAM MARTIN.
